RALPH L. KAISER, OF OAKLAND, CALIFORNIA.

COMBINATION FOLDABLE TABLE AND BENCH.

1,391,833.

Specification of Letters Patent. Patented Sept. 27, 1921.

Application filed November 10, 1920. Serial No. 423,149.

To all whom it may concern:

Be it known that I, RALPH L. KAISER, a citizen of the United States, residing at Oakland, in the county of Alameda and State of California, have invented certain new and useful Improvements in Combination Foldable Tables and Benches, of which the following is a specification.

My invention is a combination foldable table and bench and comprises a table which may be folded in the form of a box and foldable benches, which table and benches when folded may be strapped together on the running board of an automobile.

Referring to the annexed drawing in which my invention is illustrated and which forms a part of this specification,

Figure 1 is an inverted perspective of my table unfolded for use.

Fig. 2 is a cross section of my table taken on line 2—2 of Fig. 1.

Fig. 3 is a cross section of my table taken on line 3—3 of Fig. 1.

Fig. 4 is a view of the forked engaging end of one of the leg braces.

Fig. 5 is an edge view of the connecting ends of one of the table legs.

Fig. 6 is a side view of the connecting end of one of the legs.

Fig. 7 is a side view of the table folded in the form of a box.

Fig. 8 is a cross section of my folded table taken on line 8—8 of Fig. 7.

Fig. 9 is a fragmentary horizontal section of my folded table taken on line 9—9 of Fig. 8.

Fig. 10 is a side view of two folded benches placed together.

Fig. 11 is an underside view of one of my benches folded.

Fig. 12 is a side view of one of my benches unfolded and set up in position for use.

Fig. 13 is a side view of one of the end walls.

The table top 1 includes four rectangular leaves 2, 3, 4 and 5, the abutting edges of said leaves being beveled on their under side and the abutting side beveled edges of the leaves 2 and 3, 3 and 4, and 4 and 5 being hinged together by hinges 6, 7 and 8 secured respectively thereto, so that said hinges are under the table when it is unfolded and inside the table when it is folded. On the underside of the leaves 2, 3, 4 and 5 at the ends thereof are secured transverse cleats 9,

the ends of which are beveled so as not to interfere with the folding of the leaves. On the underside of the leaf 2 are secured straps 10, 11 and 12, which are partly offset 60 intermediate their ends. On the underside of leaf 5 are secured straps 13, 14 and 15 which are partly offset from the leaf intermediate their ends. A pair of legs 16 and 17 are pivoted together intermediate their 65 ends by a bolt 18, on the inner end of which screws a nut 19. On the outer edge at the upper end of the legs 16 and 17 are secured cleats 20 and 21 which extend outwardly from the legs and are adapted to be inserted 70 under the offset portion of the straps 10 and 13 whereby the table top is mounted on said legs. A bar 22 has a cleat 23 secured to its upper edge and projecting from one end which is adapted to be inserted under 75 the offset portion of the cleat 13 with the bar resting against legs 16 and 17 and engaging the underside of the table top. A bolt 24 extends through the upper end of the leg 16 and through an aperture in the bar 22, 80 and a fly nut 26 screws on the end of said bolt against said bar, said bolt and the cleat 23 and strap 13 holding the bar against the under side of the table top to hold the leaves 2, 3, 4 and 5 flat. A brace 30 is 85 hinged at one end by a hinge 31 to the underside of the leaf 4 and has a fork 32 secured to its other end adapted to straddle the inner end of the bolt 18 and to be engaged by fly nut 19. said brace holding the 90 legs 16 and 17 rigid in supporting position. A pair of legs 36 and 37 are pivoted together intermediate their ends by a bolt 38 on the inner end of which screws a nut 39. On the outer edge at the upper end of the 95 legs 36 and 37 are secured cleats 40 and 41 which extend outwardly from the legs and are adapted to be inserted under the offset portion of the straps 11 and 15 whereby the table top is mounted on said legs. A bar 42 has a cleat 43 secured to its upper edge and projecting from one end which is adapted to be inserted under the offset portion of the cleat 12 with the bar resting against the legs 36 and 37 and engaging the under side of the table top. A bolt 44 extends through the upper end of the leg 37 and through an aperture in the bar 42, and a fly nut 46 screws on the outer end of said bolt against said bar, said bolt and the cleat 43 and strap 12 holding the bar against 100 the underside of the table top to hold the 105 underside of the table top to hold the 110 underside of the table top to hold the

leaves of the table flat. A brace 50 is hinged at one end by a hinge 51 to the underside of the leaf 4 and has a fork 52 secured to its other end adapted to straddle the inner end of the bolt 38 and to be engaged by fly nut 39, said brace holding the legs 36 and 37 rigid in supporting position.

Square end walls 60 are hinged by a loose pin hinge at one edge to the inside of leaf 3 adjacent the inside of the cleats 9 at the ends of said leaf. On the inside of one of the end walls 60 is secured a plate 61 on which is a pin 62 and a lug 63. To the inside of the leaf 5 is secured a bracket 65 to which is pivoted a latch 66 provided with a notch 67. The benches 70 and 71 each include a rectangular box-shaped top 72, to the underside of the top wall of which near the ends thereof are hinged the upper end of legs 73. Foldable braces 74 are hinged at one end to the underside of the top wall of the top 72 and at their other end to the legs 73. Rectangular blocks 75 and 76 are secured in the ends of the top 72 against which the legs 73 are braced when they are unfolded in supporting position as shown in Fig. 12. To the blocks 75 are secured pins 77 adapted to be inserted into holes 78 in the blocks 76 whereby the two benches 70 and 71 are held together with the legs 73 folded up in the tops of the benches.

The legs of the table and the bars 22 and 42 may be removed from the table top upon removing the fly nuts 24, 44 and 39, and 19. The braces 30 and 50 may then be folded

against the inside of leaf 4. The leaves 3, 4 and 5 may then be folded on their hinges and the latch 66 sprung over the lug 63 with the pin 62 engaging the notch 67 to lock said leaves in folded position. The legs 16 and 17 and the legs 36 and 37 may then be folded on their pivots and said legs and the bars 22 and 42 placed inside box-folded leaves. The leaf 2 may then be folded against the edge of the end walls 60 and the folded table placed on the running board of an automobile with said leaf resting upon the running board. The folded box and contents and the folded 50 benches 70 and 71 may then be strapped together on the automobile running board.

Having described my invention, I claim:

A foldable table including a plurality of leaves hinged together, two pairs of legs, each pair being pivoted together, cleats on the upper end of each of said legs, straps secured to the underside of the outer leaves into which said cleats are introduced to mount the table leaves unfolded on said legs, two bars, a cleat on one end of each bar, a strap on the underside of each of the outer leaves to receive a cleat on one bar with said bars against the underside of said leaves, each of said bars having a hole in its other end, a bolt extending through the upper end of one of the legs of each pair and through said holes, and nuts screwing on the end of said bolts.

In testimony whereof I affix my signature. 70

RALPH L. KAISER.
